Henry J. Schmidt,
Attorney.

UNITED STATES PATENT OFFICE

1,980,689

ELECTRIC HEATING ATTACHMENT FOR
ELECTRIC FANS

Louis Ludwig, Brooklyn, N. Y.

Application April 8, 1933, Serial No. 665,091

4 Claims. (Cl. 219—39)

The invention relates to electric heaters of a type which is attachable to electric fans. Its main object is to provide an efficient electric heater which can be attached to the guard of any portable, electric fan so that the currents of air passing through the heater will be heated by it. Another object is to provide the heater with means whereby its resistance element and the motor of the fan may be electrically connected in series parallel. A further object is to provide a heater of simple, neat and inexpensive construction which can be operated in connection with any electric fan without necessitating any alteration in any of its parts.

These and various other objects and advantages will be readily understood from the following description and from the accompanying drawing of a preferred embodiment of the invention in which, however, various modifications may be made without departing from the scope of the appended claims.

In the drawing:

Fig. 1 is a front elevation of the preferred embodiment of the heater shown with certain parts of the guard broken away;

Fig. 2 an enlarged, cross-sectional, side elevation of a special attachment plug used with the heater; and

Fig. 3 a side elevation of Fig. 1, taken on line 3—3 and shown partly in cross-section.

Referring now to all the views, simultaneously, the heater comprises a rod 10 which is formed into a spiral and on which a plurality of supporting members 11 are strung in spaced relation to each other. These spaced members are made of insulating and heat-resisting material and support the heating element 12 which is also formed in a spiral and preferably consists of a coiled resistance wire. I prefer to arrange the rod and the heating element in such a manner that they both be in the same plane, as plainly shown on the drawing.

Besides the supporting members 11, which support the resistance coil and maintain it in its correct position, other supporting members 13, 14, 15 and 16 are employed for securing the rod and the resistance coil to the guard frame 17. This guard frame is provided with radial bars 18 which guard the front of the heater, and with a plurality of hooks 19 which are constructed to hook on to the fan guard 20, a part of which is shown in Fig. 3. Each hook is provided with a sliding collar 21 which is pressed against the rod of the fan guard and held in place by a screw 22.

Asbestos-covered wires 23 and 24 are connected, respectively, to the inner and outer ends of the resistance element, while another asbestos-covered wire 25 is tapped into the element approximately halfway between its ends. These three wires are parts of a cable 26 which is supported in the member 16 and connected to the attachment plug 27. The construction of the attachment plug, which is plainly shown in Fig. 2, will now be described.

It consists of a housing 28 in which an insulating washer 29 is secured. A prong 30, which is made integral with a contact blade 31, is secured to the washer. Another prong 32 and another blade 33 are also secured to the washer, but these are separate pieces and are insulated from each other by the washer. The wire 23 connects the inner end of the resistance element with the screw 34 and, consequently, with both the prong 30 and the blade 31. The wire 24 connects the outer end of the resistance coil with a screw 35 associated with the prong 32, while the tap wire 25 connects the center of the coil with a screw 36 associated with the blade 33. The cable 26 passes through an opening 37 in the top of the housing. An extra washer 38 is preferably inserted in the end of the housing to hide the wire connections. Two openings 39 and 40 are provided in the top of the housing through which the prongs of the attachment plug of the fan may be inserted to contact with the blades 31 and 33.

It will be seen that the construction of this attachment plug is such that, when the prongs 30 and 32 are connected to a source of electric current and the prongs of the attachment plug of the fan are contacting with the blades 31 and 33, the resistance element and the fan motor will be connected in series parallel. To illustrate this: If the current enters through prong 32, it will flow through wire 24, resistance coil 12, tap wire 25, blade 33 and, through the fan motor circuit, back to blade 31 with its integral prong 30. At the same time a current will continue through the entire length of the resistance element and, through wire 23, back to the blade 31 and prong 30.

While I have shown the resistance element tapped about midway between its ends, it will be understood that it might be tapped at other points in order to increase or decrease the resistance in the fan motor circuit and accordingly change the speed of the fan. An extra resistance may also be inserted in the circuit to further decrease the speed of the fan.

Having described my invention and its operation, what I claim as new and wish to protect by Letters Patent is:

1. An electric heater of the class described, comprising a resistance element, a support for said element, means for securing the heater to the front face of an electric fan, the resistance element connected by wires to an attachment plug having prongs for tapping an electric current, and means contained within said attachment plug whereby the attachment plug of the fan to which the heater is attached may be connected to the heater attachment plug in such a manner that the circuit of the electric fan motor will be connected in series parallel with the resistance element of the heater.
2. An electric heater of the class described, comprising a resistance element, a support for said element, means for securing the heater to the front face of an electric fan, the resistance element connected by wires to an attachment plug having prongs for tapping an electric current, and means contained within said attachment plug whereby the attachment plug of the fan to which the heater is attached may be connected to the heater attachment plug in such a manner that the circuit of the electric fan motor will be connected in series parallel with a part of the resistance element.
3. An electric heater of the class described, comprising a spirally-wound and spiral-shaped resistance element, a spiral-shaped rod provided with insulating and heat resisting means for supporting said resisting element, the resistance element and the rod located within the convolutions of each other so as to lay in a common plane, a support for said rod, said support constituting a guard for the heater, means for securing the heater to the front face of an electric fan, the resistance element connected by wires to an attachment plug having prongs for tapping an electric current, and means contained within said attachment plug whereby the attachment plug of the fan to which the heater is attached may be connected to the heater attachment plug in such a manner that the circuit of the electric fan motor will be connected in series parallel with a part of the resistance element of the heater.

convolutions of each other so as to lay in a common plane, a support for said rod, means for securing the heater to the front face of an electric fan, the resistance element connected by wires to an attachment plug having prongs for tapping an electric current, and means contained within said attachment plug whereby the attachment plug of the fan to which the heater is attached may be connected to the heater attachment plug in such a manner that the circuit of the electric fan motor will be connected in series parallel with a part of the resistance element of the heater.

4. An electric heater of the class described, comprising a spirally-wound and spiral-shaped resistance element, a spiral-shaped rod provided with insulating and heat resisting means for supporting said resisting element, the resistance element and the rod located within the convolutions of each other so as to lay in a common plane, a support for said rod, said support constituting a guard for the heater, means for securing the heater to the front face of an electric fan, the resistance element connected by wires to an attachment plug having prongs for tapping an electric current, and means contained within said attachment plug whereby the attachment plug of the fan to which the heater is attached may be connected to the heater attachment plug in such a manner that the circuit of the electric fan motor will be connected in series parallel with a part of the resistance element of the heater.
